UNITED STATES PATENT OFFICE.

CHESTER W. LARNER, OF PHILADELPHIA, PENNSYLVANIA, ASSIGNOR TO THE WILLIAM CRAMP & SONS SHIP & ENGINE BUILDING COMPANY, A CORPORATION OF PENNSYLVANIA.

FLOW-CONTROL SYSTEM.

Application filed March 17, 1920. Serial No. 366,676.

To all whom it may concern:

Be it known that I, CHESTER W. LARNER, a citizen of the United States, residing at Philadelphia, in the county of Philadelphia and State of Pennsylvania, have invented certain new and useful Improvements in Flow-Control Systems, of which the following is a specification.

This invention relates to flow control systems and particularly to a valve control means for the flow through water mains. The chief object of the invention is to provide simple and efficient means for governing the movement of a main control valve so that its degree and rate of opening or closing are at all times under complete control.

To avoid water hammer or sudden rushes of flow in the operation of water main valves it is often necessary to move the valve slowly when near its seat though the remainder of the valve stroke may be at any desired rate. For instance in opening the valve of a hydraulic power system, a too quick opening of the valve may admit the full flow suddenly into empty spaces with great rush of flow and abrupt stopping as the spaces are filled and resultant dangerous rise in pressure. In such case the proper operation is to open the control valve slightly and hold it partially open until the empty spaces are filled or "primed" after which the opening movement of the control valve may be resumed at any desired rate.

Similarly in closing the valve it is usually the last portion of the closing movement that most suddenly decelerates the flow and causes water hammer and by easing off or "damping" this closing movement in its final phases the deceleration of the stream will be sufficiently gradual to avoid dangerous rise in pressure.

In the apparatus of this invention the main control valve at any point in its opening or closing may be readily slowed down or stopped and then again accelerated so that the operator is enabled to exercise the desired control and effect the proper damped or interrupted movement of the valve. The movement of the valve is synchronous with the movement of the operating mechanism.

In the accompanying drawings illustrating one embodiment of the invention,

Fig. 1 is a diagrammatic plan view of a water main control system and

Fig. 2 is vertical sectional view on line 2-2 of Fig. 1.

In the specific embodiment of the invention illustrated in the accompanying drawings a water power main 1, 2 is provided with an enlarged portion 3 within which moves a valve plunger 4 seating at 5 across the neck of the enlarged portion 3 to close the main and moving back in cylinder 6 to open the main. The valve plunger 4 is hollow and provided with piston 7 moving in cylinder 6 and the body of the valve 4 is of reduced diameter providing a space 8 between the piston 7 and the end 9 of the cylinder 6. A by-pass 10 is provided for admitting fluid pressure from the water way 12 into the space 8 when the valve plunger is in its closed position and an opening 13 is provided in the cylinder 6 for admitting fluid pressure from the water way 12 to the space 15 on the other side of the valve plunger 4 and within the cylinder 6.

The annular space 8 is connected to exhaust through a valve 24 and the space 15 is similarly connected to exhaust through a valve 23 while another outlet from this space 15 is provided by the opening 20 in the nose of the valve plunger 4 controlled by valve 21. Valve 23 is considerably larger in flow capacity than port 13 in order that pressure may be exhausted from chamber 15 by valve 23 notwithstanding the simultaneous admission of pressure through port 13. To open valve plunger 4 valve 23 is opened to exhaust pressure from chamber 15 whereupon pressure through by-pass 10 into annular space 8 against piston 7 will begin the opening movement of the valve plunger 4, valve 24 being closed. The partial opening of plunger 4 will close by-pass 10 by the end 9 of the cylinder 6 and thereafter pressure for the annular chamber 8 will leak in through a clearance provided between the plunger 4 and this end 9 of the cylinder 6 so that so long as valve 23 is open and valve 24 closed the plunger 4 will continue to move to its open position. In the fully open position the piston 7 of plunger 4 will move over and restrict but not entirely close the port 13 reducing the pressure supply to the chamber 15 thus tending to hold

the plunger 4 in its open position by co-operation with valve 21 in a manner herein-after more specifically described. To close plunger 4 valves 21 and 23 are closed and 5 valve 24 opened so that pressure will be exhausted from the annular chamber 8 and admitted through the port 13 behind the plunger to close it.

Controlling of the port 13 and by-pass 10 being automatic by the movements of the plunger 4 the governing of valve plunger 4 is effected by the operation of valves 21, 23 and 24 and to place this control conveniently in the hand of the operator so that by 15 movement of a single control member he may properly coordinate the movements of these valves, mechanism is provided which in the specific embodiment shown in the drawings comprises an operating rod 30 moved upward to cause a closing movement 20 of plunger 4 and downward to cause an opening movement of the same. To the rod 30 is pivoted a floating lever 31 connected at the end 32 to mechanism controlling the 25 valve 21 and at the end 33 to mechanism alternatively controlling the valves 23 and 24. The end 32 of the lever 31 is connected by link 34 to arm 35 of shaft 36 passing into the space 15 within the cylinder 6 and 30 carrying at its inner end the arm 37 linked by rod 38 to the valve member 21 sliding in bearing 39 in plunger 4. It is obvious that upward movement of the rod 30 will draw upward on link 34 to tip arm 37 to 35 the right (Fig. 2) to shut valve 21. Upward movement of operating rod 30 will also draw upward on link 41 and turn counter-clockwise arm 42 and lever or walking beam 43 both of which are connected to 40 a rotatable stud 44 in a bearing 45 supported by the valve casing. The downward movement of the left end of lever 43 closes valve 23 while the upward movement of the right end of lever 43 opens valve 24 so that 45 the shutting of valve 21 is accompanied by the opening of valve 24 and the closing of valve 23 and it is obvious that the main valve plunger 4 will be caused to move in a direction to close.

50 Valves 23 and 24 are preferably of the plunger type shown having their plungers 53 and 54 controlled by rods 63 and 64 respectively extending upward through the forked ends of lever 43 and downwardly 55 spring pressed by springs 48 and 58 so that both of the valve rods 63 and 64 are normally pressed downward and both the valves 23 and 24 normally closed.

With the linkages as above described and 60 following a slight upward movement of operating rod 30 it is apparent that the resultant closing of the plunger 4 will permit the arm 37 to tip counter-clockwise (Fig. 2) letting the floating lever 31 turn clockwise 65 and with it the lever 43 also clockwise so

as to lower control rod 64 of valve 24 to restrict said valve, the previous counter-clockwise movement of lever 43 having compressed spring 58 and raised said rod. Unless the operating rod 30 is further moved 70 upward then the closing movement of valve plunger 4 will automatically close valve 24 to restrict the outflow from the space 8 and stop the closing movement of the plunger. The operator therefore by proper manipulation of the rod 30 may move the plunger 4 to any extent desired. The rate of movement of the valve 4 is also dependent on the rate of operation of rod 30 and it may be preferable in installations where there is danger of 75 excessive rise in pressure upon too sudden movement of the valve 4, to limit the rate of movement of the operating rod 30 in the hands of the operator so that a certain rate of movement of the valve 4 cannot be exceeded.

When the closing movement of the valve plunger 4 is completed by the seating of the valve if the final increment of the valve movement which permits rod 38 to move to the right (Fig. 2) to tip the lever 43 clockwise does not permit control rod 64 to entirely close plunger 54 of valve 24 under the action of spring 58 then the movement of rod 30 should be reversed slightly by the operator until valve 24 is permitted to close so that all the valves 21, 23 and 24 will in the closed position of the plunger 4 be normally closed while the port 13 and by-pass 10 will be open.

To open the valve plunger 4 the operator moves operating rod 30 downward tending to draw valve 21 open and at the same time tending to turn lever 43 clockwise to draw up control rod 63 against the compression of spring 48 and thus open the plunger 53 of valve 23 so that pressure is exhausted from the chamber 15 while it is admitted to chamber 8 through by-pass 10. When operating rod 30 is drawn downward the first effect is to transmit a pressure to rods 34 and 41 thus pressing the left end of lever 43 up against the enlargement 49 of rod 63 and tending to compress spring 48. At 115 the same time the pressure on rod 34 is transmitted through the various connections to valve 21 and if the adjustment of spring 48 gives sufficient resistance, valve 21 will be pulled off its seat before rod 63 is lifted. In this case valve 21 will open until it is stopped by bearing 39 and then valve 23 will be opened, but otherwise valve 23 will open first starting the plunger open and valve 21 would open only when the pressure on the outside of the plunger nose has accumulated sufficiently.

This operation, of course, at the same time leaves valve 24 closed by the pressure of spring 58 and if the operator continues the downward movement of rod 30 the open-

ing movement of the main plunger 4 will continue in a way similar to that already described for the closing movement of the plunger. In either case if the plunger is 5 either completely opened or fully closed the motion of rod 30 should be slightly reversed to restore walking beam or lever 43 to its horizontal position and permit valve 23 or valve 24 to close.

10 In valves of the type described it is of course important that plunger 4 should be held positively in both the open and closed positions so that it cannot accidentally drift closed when it is open or drift open when 15 it is closed. Furthermore this result should not be accomplished by a continuous exhaust of pressure through valves 23 and 24 because of the water waste which would result and also because of the destruction effects of continuous flow through the valves. Valves 23 and 24 should always be closed except when plunger 4 is in operation.

With valves 23 and 24 closed if plunger 4 is closed it will be held in that position 25 by the unbalanced pressure of the conduit applied on the entire area of the plunger seat and it is impossible for plunger 4 to open accidentally. When plunger 4 is open, however, it can be held in that position only 30 by its own inertia and such difference of pressure inside and outside of plunger 4 as may be effected without opening valve 23.

When plunger 4 is open and there is no 35 flow in the conduit the pressure in chambers 15 and 8 and waterway 12 is equalized by leakage communication between them and plunger 4 is held open only due to its weight. This, however, is sufficient since 40 there is no tendency for it to close in still water.

If, however, water is flowing through the 45 valve the pressure communicated to chamber 15 through restricted port 13 will be higher than the pressure exerted by the flowing water on the outside of plunger 4 because the velocity of flow at the former point is lower than at the latter and unless some means be provided for equalizing 50 these pressures the plunger 4 may start to close and automatically open valve 23 by means of the connections between plunger 4 and valve 23. This tendency is corrected in the valve described by the use of valve 21 which is so connected to rod 30 that when plunger 4 is open valve 21 is also open thus equalizing the pressures inside and outside of the plunger 4 or, if suitably designed, reducing the pressure in chamber 15 below that on the outside of the plunger nose by utilizing the suction effect of the flowing water on the nozzle in the nose of the plunger. This effect is more readily accomplished by restricting the pressure supply through port 13 but port 13 cannot be entirely cut off by plunger 4 in its open.

position because there would then be no means of supplying fluid to chamber 15 to begin the closing movement of plunger 4.

This system of control combines two alternative sets of movements. When valve 70 23 is open valve 24 is necessarily closed and when valve 24 is open valve 23 is necessarily closed and similarly when pressure is applied to open valve 21 it is also necessarily applied to open valve 23 and close 75 valve 24 and when the pressure is exerted to close valve 21 it is also exerted to open valve 24 and close valve 23. This distribution of the valve movements is automatically attended to by the mechanism shown 80 without any attention on the part of the operator who simply moves the control rod 30. The movement of the valve may be interrupted at any point and the rate of movement is necessarily dependent upon the 85 rate of movement of operating rod 30 so that in the hands of a skillful operator the plunger 4 may be rapidly moved when away from its seat with a damping or interruption of the movement when near its seat. This system may therefore be utilized 90 to secure both the priming and damping characteristics often necessary to avoid undue rise in pressure in the system and at the same time the remainder of the valve 95 movement may approximate closely the highest desired rate.

I claim:

1. In a system for controlling the flow of a fluid the combination with a main valve, 100 of a control member therefor, a floating differential element actuated by said control member and mechanism operated alternatively by said element to open or close said main valve comprising alternatively operated fluid pressure valves.

2. In a flow control system the combination with a main valve, of fluid pressure control means therefor comprising a plurality of alternatively operated valves and another valve operable alternatively with one of said plurality of valves, and means for automatically controlling the interaction of 110 said valves.

3. In a flow control system the combination with a main valve, of fluid pressure control means therefor comprising a plurality of alternatively operated valves, a cooperating valve and a floating differential element selectively actuating certain of said 120 valves and dependently controlling the operation of said cooperating valve.

4. In a flow control system the combination with a main valve, of means for closing or opening said valve comprising an operating member, a floating differential element actuated thereby, and fluid pressure control means comprising valves cooperating in alternative sets and controlled by said member.

5. In a system for controlling the flow of a fluid the combination with a main valve having a piston portion with fluid pressure chambers on opposite sides thereof, of valves controlling the exhaust of pressure from said respective chambers, and fluid pressure means for operating said valves comprising a connection to said main valve adapted to limit the movement of the main valve by a predetermined movement of said operating means.
6. In a flow control system the combination with a main conduit valve having oppositely acting fluid pressure chambers and permanent connections permitting conduit pressure to separately pass to said chambers, of exhaust valves of greater discharge capacity than said pressure connections and adapted to alternatively exhaust the pressure from said chambers, and means for operating said valves comprising a control member relatively movable with respect to said exhaust valves during movement of the main valve to limit the movement of the main valve according to the movement of the control member.
7. In a flow control system the combination with a main conduit valve having a tapering end and a passage therethrough connecting the interior of said main valve with the fluid in said conduit, a valve controlling said passage, a second valve controlling the fluid pressure in said main valve, and means operating both of said control valves by the movement of said main valve.
8. In a flow control system the combination with a main valve controlling the flow through a conduit, of governing means therefor comprising an actuating member, a floating differential lever connected thereto, connections between said lever and said main valve, a plurality of fluid pressure control valves, and fluid pressure means for alternatively operating said last named valves and connected to said lever.
9. In a flow control system the combination with a main conduit valve having a piston portion between fluid pressure chambers and means permitting pressure to pass from said conduit to said chambers, of valves for alternatively exhausting the pressure from said chambers, and fluid pressure means for operating said valves comprising a floating differential lever connected to the main valve to limit the movement of the main valve according to the movement of the control member.
10. In a flow control system the combination with a main conduit valve having oppositely acting fluid pressure chambers and a tapered end with an opening from one of said chambers to a region of low pressure in the fluid way, of permanently open high pressure connections to said chambers from said fluid way, a valve for said low pressure opening from one of said chambers, an exhaust valve for the other of said chambers, and control means alternatively operating said valves and automatically actuated by movement of the main valve to limit the movement of the main valve according to a predetermined movement of the control means.
11. In a flow control system the combination with a main conduit valve having oppositely acting fluid pressure chambers and means permitting pressure to pass from said conduit to said chambers, of valves for alternatively exhausting the pressure from said chambers, and fluid pressure means for operating said valves comprising a floating differential member connected to the main valve to automatically hydraulically balance said main valve and limit the movement of the main valve according to the movement of the control means.
12. In a flow control system the combination with a main conduit valve having oppositely acting fluid pressure chambers permanently open to pressure from the fluid way, of exhaust valves for said chambers and operating means for said exhaust valves comprising a single member alternatively opening said exhaust valves and connected to said main plunger so as to be movable therewith to automatically hydraulically limit the movement of said plunger according to a predetermined movement of said control means.
13. In a flow control system the combination with a main valve for controlling the flow through a conduit, of fluid pressure operating means therefor, a plurality of valves controlling the movement of said main valve, a lever for alternatively opening one or the other of a pair of said valves, a second lever for alternatively actuating another valve and said first named lever and an operating member for actuating said second named lever.

CHESTER W. LARNER.
